Application July 9, 1941, Serial No. 191,996

Term of patent 14 years

To all whom it may concern:

Be it known that we, Clifford M. Payne and Joseph M. Majewski, Jr., residing at Kansas City, in the county of Jackson and State of Missouri, have invented a new, original, and ornamental Design for a Fruit Juice Extractor, of which the following is a specification, reference being had to the accompanying drawing, forming part thereof, in which;

Fig. 1 is a perspective view of the fruit juice extractor, showing our new design, the upper juice expressing member being shown in its raised position.

Fig. 2 is a top plan view of the fruit juice extractor.

Fig. 3 is a side elevational view of the fruit juice extractor, the upper juice expressing member being shown in its closed position.

We claim:

The ornamental design for a fruit juice extractor, as shown.
